DESIGN FOR A COMMEMORATIVE EMBLEM

James M. Reardon, Minneapolis, Minn.

Application January 23, 1941, Serial No. 98,309

Term of patent 3½ years

To all whom it may concern:

Be it known that I, James M. Reardon, a citizen of the United States, residing in Minneapolis, county of Hennepin, and State of Minnesota, have invented a new, original, and ornamental Design for a Commemorative Emblem, of which the following is a specification, reference being had to the accompanying drawing, forming part thereof.

Fig. 1 is a front elevational view of a commemorative emblem showing my new design; and

Fig. 2 is a bottom edge view thereof.

I claim:

The ornamental design for a commemorative emblem, substantially as shown.

JAMES M. REARDON,
